ADJUSTABLE DOOR HANGER
Rudolph Reu Boiu, Glendora, Calif.
(339 S. Irwindale Ave., Azusa, Calif.)
Filed Feb. 10, 1961, Ser. No. 88,379
6 Claims. (Cl. 16—105)

This invention relates to an adjustable door hanger, particularly for sliding doors.

An object of the present invention is to provide an adjustable door hanger for sliding doors that automatically retains its adjusted position and, therefore, is not subject to maladjustment as may result from accidental loosening or tightening of clamping or locking screws or nuts.

Another object of the invention is to provide door hanger means that may be adjusted with easy facility by means of a single tool in a one-handed operation, thereby enabling accurate adjustment quickly and easily.

This invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description and which is based on the accompanying drawing. However, said drawing merely shows, and the following description merely describes one embodiment of the present invention, which is given by way of illustration or example only.

In the drawing, like reference characters designate similar parts in the several views.

FIG. 1 is a vertical sectional view through the framing of a sliding door showing a preferred embodiment of the present invention.

FIG. 2 is a longitudinal sectional view as taken on the line 2—2 of FIG. 1.

FIG. 3 is a similar view with the present door hanger in another adjusted position.

FIG. 4 is an enlarged cross-sectional view taken through the adjustment portion of the present hanger.

FIG. 5 is a similarly enlarged longitudinal sectional view of a pivot construction for the adjustable member of the hanger.

In quite the usual way a track 10 is horizontally disposed and housed within a bottom-open enclosure 11 that, ordinarily, is embodied in a partition, ceiling, or other portion of a building. A sliding door 12 is shown as disposed beneath said enclosure to close or open a space, as the case may be, between the stiles 13 at opposite ends of the enclosure 11. The present hanger 14 represents one of two similar hangers that suspend the door 12 from the track 10 so that said door may be slid longitudinally in the mentioned space between stiles 13 with the lower edge of said door suitably clear of the floor or floor-covering to insure against arresting of the door movement during such sliding thereof.

The present hanger 14 comprises, generally, a bracket 15 adapted to be affixed to the door, preferably the top edge thereof, an arm 16 adjustably carried by said bracket and mounting a roller 17 at one end thereof that is engaged with the track 10 to roll therealong, means 18 to pivotally frictionally connect said arm 16 to the bracket 15, and self-locking means 19 to automatically adjust and retain the adjustment of the opposite end of the arm 16 to, thereby, adjust the spacing above the door top of the roller 17, thus, adjusting the position of the lower edge of the door relative to the floor or covering thereon.

The bracket 15 comprises an angle member having one leg thereof 20 affixed to the top edge of door 12 and the other leg 21 vertically disposed. Said leg 21 is shown

2

as having a hole 22 that is near one edge 23 of said leg, and a slot 24 between hole 22 and the opposite edge 23a of said bracket leg 21.

The arm 16 has a flatwise engagement with one face of bracket leg 21. The end thereof opposite to the end of arm 16 that has the roller 17 has an enlarged circular opening 25 therein and, between said opening and the roller 17, a small hole 26 is provided.

The roller 17 is preferably of the anti-friction type and is advantageously made of nylon or other suitable long-wearing plastic material. In this case, said roller extends laterally from arm 16 so as to be disposed over the leg 20 of the bracket 15.

The pivot means 18 is shown as a stud or rivet 27 that extends through slot 24 and hole 26, with a head 28 thereon bearing against the outer face of bracket leg 21 and the end 29 opposite said head swaged over a washer 30 that is disposed against the outer face of arm 16. The pivot 18 is made to be frictionally tight, yet enabling the arm to move around the axis of rivet 27 and said rivet to move along the slot 24.

The self-locking arm-adjusting means 19 is shown as a stud 31 that extends through hole 22 in the bracket leg 21 and provided with a polygonal or similar head 32 that resides on the outer side of said bracket leg 21, a compression washer 33 between said leg 21 and the head 32, and an eccentric circular disc 34 connected, as by staking, to the stud 31 and of a diametral size to fit in the circular opening 25 in the arm 16.

It will be clear that a tool applied to head 32 to turn the same will turn said eccentric disc on the axis of stud 31 and, because of the friction imposed by the compression washer 33, said disc will remain in the rotated position of adjustment until moved by turning of the stud head. It will be clear that turning of the eccentric disc 34 causes the arm 16 to move around its pivot as before described, thereby causing the roller 17 to have a position relative to the top edge of the door 12 that varies according to the adjusted rotational position of the disc 32. It

will also be clear that the friction provided at both means 18 and 19 will hold the adjustment. FIGS. 2 and 3 show that the door may be raised or lowered as desired to achieve the bottom-edge clearance from the floor or a covering thereon as needed for smooth sliding operation of the door along the track 10.

The slot 24 is shown as sloping downward from the cam end of the bracket. This slope enables maximum adjustment of the arm 16, since the high adjustment, as in FIG. 2, has the rivet 27 in the high end of the slot and low adjustment, as in FIG. 3, has the rivet in the low end of said slot.

While the foregoing has illustrated and described what is now contemplated to be the best mode of carrying out the invention, the construction is, of course, subject to modification without departing from the spirit and scope of the invention. Therefore, it is not desired to restrict the invention to the particular form of construction illustrated and described, but to cover all modifications that may fall within the scope of the appended claims.

Having thus described this invention, what is claimed and desired to be secured by Letters Patent is:

1. An adjustable door hanger comprising a bracket adapted to be affixed to a sliding door, an arm, a friction pivot connecting an intermediate point of said arm to the bracket, said pivot embodying a slot therein whereby the arm is adapted to move longitudinally during pivotal movement thereof with respect to said bracket, a roller carried by one end of said arm and adapted to be mounted to support the door for sliding movement, and eccentric cam means adjustably carried by the bracket and engaged with the other end of the arm to move the latter around its pivot to, thereby, adjust the spaced relationship of the

70

door and the roller by movement of said friction pivot in said slot in response to adjustment of said eccentric cam.

2. An adjustable door hanger comprising a bracket adapted to be affixed to a sliding door, an arm, a friction pivot connecting an intermediate point of said arm to the bracket, said pivot embodying a slot therein whereby the arm is adapted to move longitudinally during pivotal movement thereof with respect to said bracket, a roller carried by one end of said arm and adapted to be mounted to support the door for sliding movement, said bracket having a bearing hole therein and the other end of the arm having a round opening larger than said bearing hole, a stud having bearing in said bearing hole, an eccentric disc affixed to the stud and engaged in the opening in the arm, and a polygonal head on said stud for turning the same on its axis to turn the eccentric disc in said opening to move the arm on its pivot and, thereby, adjust the spaced relationship of the door and the roller by movement of said friction pivot in said slot in response to adjustment of said eccentric disc.

3. An adjustable door hanger according to claim 2 in which resilient friction means is provided to resist adjustment of the stud and to impose a drag thereon that retains the adjusted position thereof and of the mentioned arm.

4. An adjustable door hanger according to claim 2, in which resilient friction means is provided to resist adjustment of the stud and to impose a drag thereon that retains the adjusted position thereof and of the mentioned arm, said resilient friction means comprising a compression washer between said stud and the bracket.

5. An adjustable door hanger according to claim 2 in

which resilient friction means is provided to resist adjustment of the stud and to impose a drag thereon that retains the adjusted position thereof and of the mentioned arm, said resilient friction means comprising a compression washer interposed between the head of the stud and the bracket.

6. An adjustable door hanger comprising a bracket having a vertical section and an integral section adapted to be affixed to a sliding door, an arm, a friction pivot connecting an intermediate point of said arm to said vertical section, said pivot including a slot therein whereby the arm is adapted to move longitudinally during pivotal movement thereof with respect to said vertical section, slide means carried by one end of said arm and adapted to be mounted to support the door from a rail for sliding movement thereof, and cam means adjustably connecting the other end of said arm to said vertical section whereby adjustment of said cam means moves said arm in a pivotal direction to reorientate said pivot in said slot about said pivot to adjust the spaced relationship of the door and the slide means.
